UNITED STATES PATENT OFFICE.

PAUL E. REIDER, OF PHILADELPHIA, PENNSYLVANIA.

CAR-HOPPER-RELEASING DEVICE.

1,381,661.

Specification of Letters Patent. Patented June 14, 1921.

Application filed October 23, 1920. Serial No. 420,178.

To all whom it may concern:

Be it known that I, PAUL E. REIDER, a citizen of the United States, residing at Philadelphia, in the county of Philadelphia and State of Pennsylvania, have invented 5 certain new and useful Improvements in Car-Hopper-Releasing Devices, of which the following is a specification.

One object of my invention is to provide 10 an improved device of simple and durable construction which can be readily used for releasing the bottoms of car hoppers.

Another object is to so make my device 15 that it can be easily and quickly manufactured.

These objects, and other advantageous 20 ends which will be described hereinafter, I attain in the following manner, reference being had to the accompanying drawings in which—

Figure 1 is a fragmentary elevation showing the device of my invention in operative position on the hopper controlling shaft of a freight car,

Fig. 2 is a side elevation of my improved 25 device,

Fig. 3 is a top plan view of Fig. 1,

Fig. 4 is an enlarged fragmentary view 30 showing certain of the parts in section, and

Fig. 5 is an end elevation of the bar head 35 which forms a part of my invention.

Referring to the drawings, 6 represents the side of a freight car having a bottom hopper 7 adapted to be controlled by a shaft 8, 40 which at its outer end is square in cross section. These elements are of the usual form present on freight cars of various types, and do not in themselves constitute a part of my present invention.

The device of my invention is adapted to 45 partially rotate at the shaft 8 in order to permit the opening of the hopper and I will now describe the device of my invention in detail.

An elongated bar 9 has a T-shape head 10; the head having oppositely disposed slots 11 and 12 extending entirely therethrough, as clearly shown in Fig. 4. The portions 13 of 50 the head remote from the bar 9 are circular in cross section and either of the slots 11 and 12 is adapted to receive the hooked end 13^a of a finger 14; the finger being of such shape as to partially embrace the shaft 8. The finger 14 has a lip 15 at its end opposite the hook 13 and said lip 15 is adapted to engage under the bottom surface of the shaft 55

8 when in the position shown in Fig. 1. The face 16 of the outer end of the head 10 has ribs or teeth thereon adapted to bite into the shaft 8 so that when the bar is moved downwardly the shaft 8 will be partially rotated, which action is necessary prior to the releasing of the hopper bottom.

It will be noted that by having the portions 13 of the head circular in cross section 60 that the finger 14 can be released from any of the slots by completely turning the finger so as to free the hooked end 13^a from the head portions 13. Thus if either end of the head becomes broken during use the hook 70 13^a can be inserted in the slot of the opposite end of the head.

In order to prevent loss of the finger 14, I provide a chain 17 and attach the opposite ends of this chain to the finger 14 and to the 75 bar 9, the chain 17 being sufficiently long to permit the hook 13^a to be inserted in the opposite slot from that in which it is positioned in the drawings.

Thus in the device of my present invention 80 it is unnecessary to use any pivot pins or connected hinges since the device will effectively operate merely by the connection of the hook as above described.

While I have described my invention as 85 taking a particular form, it will be understood that the various parts of my invention may be changed without departing from the spirit thereof, and hence I do not limit myself to the precise construction set forth, but 90 consider that I am at liberty to make such changes and alterations as fairly come within the scope of the appended claims.

Having thus described my invention, what I claim as new and desire to secure by Letters Patent is:—

1. A device of the character described including an elongated bar having a head at one end; said head including a slot; and a finger having a hook adapted to be inserted 100 within said slot and pivot on a portion of the head immediately adjacent said slot and remote from said bar; substantially as described.

2. A device of the character described including an elongated bar having a head projecting therefrom at one end; said head including a slot; and a finger having an angular portion and a hook, said hook being adapted to be inserted within said slot and 105 pivot on a portion of the head immediately adjacent said slot and remote from said

bar; the surface of the outer end of said head having ribs thereon oppositely disposed to an angular portion of said finger; substantially as described.

5 3. A device of the character described including an elongated bar having a head on one end provided with a plurality of slots and a clamping finger including a hook adapted to be inserted through any one of said slots to pivotally rock on a portion of

said head adjacent the slot in which it is inserted; substantially as described.

In testimony whereof I have signed my name to this specification in the presence of two subscribing witnesses.

PAUL E. REIDER.
